SIGNAL LAMP LENS

Robert I. Nagel, Skokie, Ill., assignor to Dominion Auto Accessories Limited, Toronto, Ontario, Canada

Filed Nov. 29, 1974, Ser. No. 528,165

Term of patent 14 years

Int. Cl. D10—06; D26—06

U.S. Cl. D48—32 A

FIG. 1

FIG. 2

FIG. 3

FIG. 4

FIG. 1 is a front elevational view of the signal lamp lens showing my new design.

FIG. 2 is a side elevational view of the same.

FIG. 3 is a bottom view of the same.

FIG. 4 is a fragmentary sectional view of the same on an enlarged scale taken along the line 4—4 in FIG. 1.

I claim:

The ornamental design for a signal lamp lens, as shown and described.
